UNITED STATES PATENT OFFICE.

TIMOTHY LEMAIRE, OF TROY, NEW YORK, ASSIGNOR OF ONE-HALF TO
GEORGE H. BELL, OF SAME PLACE.

DESIGN FOR A FRAME FOR CLOTHES-LINE HOLDERS.

SPECIFICATION forming part of Design No. 31,792, dated November 7, 1899.

Application filed August 4, 1899. Serial No. 726,205. Term of patent 7 years.

To all whom it may concern:

Be it known that I, TIMOTHY LEMAIRE, of the city of Troy, county of Rensselaer, and State of New York, have invented and produced a new and original Design for a Frame for Clothes-Line Holders, and of which the following is a specification, reference being had to the accompanying sheet of drawings, forming a part thereof, of which—

Figure 1 is a side elevation of a frame for clothes-line holders, showing my design. Fig. 2 is a front view, and Fig. 3 a back view, of the same.

As illustrated in the drawings, the new and useful form of the frame for a clothes-line holder constitutes my design; and it is shown to consist of a bar B, having a flat front and back with rounded edges, the front being

designated at F and the back at B², and the letter b³ designates a bow-form bend that is 20 made centrally in the bar, and the letter H' designates a hook formed in one end of the bar, and the letter H² designates a hook formed in the other end of the bar, with both of these hooks offset from the same side of the bar 25 and from the same side of the latter as the bow b³.

Having thus described my invention, what I claim, and desire to secure by Letters Patent, is—

The design for a frame for a clothes-line holder as herein shown and described.

TIMOTHY LEMAIRE.
